US0D1038432S

(12) **United States Design Patent** (10) Patent No.: **US D1,038,432 S**
 Ling et al. (45) Date of Patent: ** Aug. 6, 2024

(54) **TESTER FOR TESTING BIOLOGICAL FLUIDS**

(71) Applicant: **ASSURE TECH. (HANGZHOU) CO., LTD.**, Zhejiang (CN)

(72) Inventors: **Shisheng Ling**, Hangzhou (CN); **Yingchong Tong**, Hangzhou (CN)

(73) Assignee: **ASSURE TECH. (HANGZHOU) CO., LTD.**, Hangzhou (CN)

(**) Term: **15 Years**

(21) Appl. No.: **29/865,302**

(22) Filed: **Jul. 18, 2022**

(30) **Foreign Application Priority Data**

Jan. 18, 2022 (CN) 202230031908.4

(51) **LOC (14) Cl.** **24-02**

(52) **U.S. Cl.**

USPC **D24/223**

(57) **CLAIM**

The ornamental design for a tester for testing biological fluids, as shown and described.

DESCRIPTION

FIG. 1 is a front view of a tester for testing biological fluids according to our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a top perspective view thereof; and,

FIG. 8 is a bottom perspective view thereof.

The broken lines depict portions of the tester for testing biological fluids that form no part of the claimed design.

1 Claim, 8 Drawing Sheets
